CURTAIN

Hugo Geller, New York, N. Y., assignor to Pat-
chogue-Plymouth Mills Corporation, New
York, N. Y., a corporation of New York

Application August 24, 1934, Serial No. 741,219

10 Claims. (Cl. 156—10)

This invention relates to improvements in curtains made from any fabricated material, and more particularly woven textile fabrics.

Heretofore curtains made from textile fabrics have been provided with a hem defining the top edge thereof but without any provision whereby the body of the curtain could be adjusted to windows of different sizes, or to compensate for shrinkage as in laundering.

10 The object of this invention is a ready-to-hang adjustable curtain made of textile fabric.

Another object is a ready-to-hang curtain having a surplus of textile fabric which may be utilized to extend the curtain and when not so utilized conserved in the form of an ornamental top or valance tending to enhance the ornamental appearance of the hung curtain.

Other objects are economy of time and labor.

According to this invention the ready-to-hang curtain fabricated of any preferred material, a woven textile fabric being preferred, is made appreciably longer than the corresponding conventional curtain previously employed and the said extension or surplus fabric top portion is provided 25 with a plurality of horizontal hemmed rod-engaging passageways positioned in spaced relation relative to each other. The uppermost passageway may constitute the extreme upper marginal edge of the curtain. The hemmed passageways are 30 preferably spaced apart at a distance therebetween generally representing the amount of shrinkage in laundering, so that when the curtain is rehung after laundering it may be suspended from another hemmed passageway constituting a new line of suspension so as to display 35 approximately the same length of curtain down hanging from the suspension rod as before.

In the drawings comprising three sheets of fourteen figures numbered Figs. 1 to 14 inclusive certain embodiments of the invention are set forth.

Fig. 1 is a front view of one form of curtain embodying the invention.

Fig. 2 is a vertical sectional view of the curtain of Fig. 1 taken along the line 2—2 looking in the direction of the arrows.

Fig. 3 is a front view of the curtain in hung position adjusted to minimum length.

Fig. 4 is a vertical sectional view of the hung curtain of Fig. 3 taken along the line 4—4 of Fig. 3 looking in the direction of the arrows.

Fig. 5 is an end view of the curtain suspended from a different hemmed passageway to effect an intermediate length adjustment.

55 Fig. 6 is an end view of the curtain suspended

from the topmost hemmed passageway to effect maximum length adjustment.

Fig. 7 is a front view of a modified construction.

Fig. 8 is a vertical sectional view taken along the line 8—8 of Fig. 7 looking in the direction of 5 the arrows.

Fig. 9 is an end view of the curtain of Fig. 7, suspended from the bottom passageway to effect minimum length adjustment.

Fig. 10 is a vertical sectional view of another 10 modified construction.

Fig. 11 is a further vertical sectional view of the curtain of Fig. 10, suspended to effect minimum length adjustment.

Fig. 12 is a vertical sectional view of another 15 modified construction; and

Figs. 13 and 14 are vertical sectional views of the curtain of Fig. 12, suspended in various ways.

Like reference characters designate corresponding parts throughout the several figures of 20 the drawings.

Referring to Figs. 1 and 2, the curtain 10 which is made of any preferred fabric or other material suitable for curtains, consists of a lower or body portion 12 and a top portion 11 constituting an 25 extension thereof and preferably made of the same fabric, although said body portion 12 and top portion 11 may be made of different fabrics if preferred united in any suitable manner as by rows of stitches adjacent the bottom hemmed 30 rod-engaging passageway 17. The top portion 11 is formed into a plurality of hemmed rod-engaging passageways 13, 15 and 17 traversing the curtain top 11 horizontally and in spaced relation one to the other, said hemmed passageways being 35 preferably of uniform size and substantially uniformly spaced. Each of the said hemmed passageways is sufficiently large to slidably receive the conventional elongated curtain rod now in vogue, although the said hemmed passageways 40 may be enlarged or diminished to slidably receive any other selected form of curtain rod. The bottom 21 of the curtain is reversely folded as indicated at 22 and sewn with one or more transverse lines of stitches 23 to form a bottom hem. The 45 side edges like the bottom edge may be hemmed or otherwise finished in any preferred manner to prevent unraveling of the fabrics. Hemmed passageways 15 and 17 are fashioned by looping the 50 fabric and stitching the same by transverse lines of stitches 19 and 20 (Fig. 2). Similarly the hemmed passageway 13 is formed by folding back the top edge of the curtain fabric one or more times for a sufficient distance and securing the 55

plies together by one or more lines of stitches 18 traversing the fabric horizontally from side edge to side edge.

The curtain may be suspended upon a suitable curtain rod 24 (Figs. 3 to 6). As illustrated in Fig. 3 the curtain 10 may be suspended from the bottom hemmed rod-engaging passageway 17. Said passageway is large enough to permit free sliding movement of the curtain upon the rod 24 so that said curtain may be pleated or adjusted to any desired width, it being understood that the curtain 10 may be suspended either as a panel or as one of a pair of curtains in accordance with the conventional practice. When curtain 10 is suspended from the bottom hemmed passageway 17 as indicated in Fig. 3 minimum length adjustment is effected, and the top portion 11 becomes in effect surplus fabric which hangs downwards in the form of a valance, the hemmed passageways 13 and 15 simulating ornamental bands traversing the curtain horizontally.

When it is desired to lengthen the curtain it may be suspended from some other selected line of suspension such as the hemmed passageways 13 or 15. With a curtain provided with three or more hemmed passageways three or more adjustments may be obtained as each hemmed passageway constitutes a different line of suspension effective to produce a different length adjustment. When the curtain 10 of Fig. 1 is suspended to effect an intermediate length adjustment, the curtain rod 24 will be passed through the hemmed passageway 15 (Fig. 5). When so suspended panel 14 and hemmed passageway 13 of the top portion 11 become surplus fabric which may be conserved for possible future use by allowing it to hang down to form an ornamental top or valance surmounting the body portion 12 adjacent the rod-engaging hemmed passageway 15 constituting the line of suspension defined by the curtain rod 24. Hemmed passageway 17 and panel 16 of top 11, are effective to extend the body portion 12, being in effect transferred from top portion 11 to body portion 12.

Similarly if it is desired to hang the curtain so as to effect maximum length adjustment the curtain rod 24 may be inserted in the hemmed passageway 13 (Fig. 6) in which event both of the hemmed passageways 13 and 15 and the panels 14 and 16 of top 11, are utilized to extend the body portion 12. In this position all of the surplus fabric is utilized as a part of the body portion 12, without any valance surmounting said body portion adjacent the curtain rod 24.

The top portion 11 may be of any preferred length and provided with any selected number of hemmed rod-engaging passageways but in practice it has been found that a top portion provided with three spaced hemmed passageways 13, 15 and 17 so as to give the top portion 11 an overall length measured from the top edge of the curtain to the seam of the lowermost hemmed passageway 17 of approximately 9 inches and having hemmed passageways adapted to freely slidably receive the conventional one inch curtain rod gives very effective results. With this arrangement when the curtain is hung to effect minimum length adjustment as illustrated in Figs. 3 and 4 the surplus fabric represented by the top portion 11 may be draped so as to form a down hanging ornamental top approximating in dimensions and simulating in appearance a conventional curtain valance.

Figs. 7, 8 and 9, illustrate another construction

wherein instead of forming the hemmed passageways individually in a single ply of fabric as shown in Figs. 1 to 6 inclusive, the fabric is doubled upon itself so as to provide a top portion 11 consisting of two plies of fabric, the hemmed passageways 13, 15 and 17 being formed by the lines of stitches 25 to 29 inclusive horizontally traversing the curtain at suitably spaced intervals to produce hemmed passageways large enough to receive the conventional curtain rod. Curtains made in accordance with this alternative construction may be suspended from any one of the hemmed passageways to effect maximum (Fig. 8), minimum (Fig. 9), or intermediate (not shown), length adjustment, in the same manner as a curtain constructed as illustrated in Figs. 1 to 6 inclusive.

Figs. 10 and 11 are sectional views showing certain other modifications which may be made if desired. The top hem 13, may be surmounted with a non-raveling top edge 41, formed by folding the fabric upon itself and securing it with a line of stitches 42. The hemmed passageways 15 and 17 may be formed so as to be displayed on opposite sides of the curtain as disclosed in Fig. 10, where the hemmed passageway 15 extends to the front, and the hemmed passageway 17 to the rear, of the curtain, so that when adjusted to minimum length, as shown in Fig. 11, the hemmed passageway 15 will be concealed behind the down hanging valance-like top portion 11.

Figs. 12, 13 and 14 disclose another modification having hemmed passageways on both sides of the curtain at a single line of suspension. At the lines of suspension to effect intermediate and minimum length adjustment the curtain is provided with the hemmed passageways 15 and 17 displayed in front, and the hemmed passageways 35 and 37 concealed behind the wall of curtain fabric. Hemmed passageways 15 and 35 may be folded at the same time, and may be secured in position by one or more lines of stitches 39; similarly hemmed passageways 17 and 37 may be folded and secured in position by one or more lines of stitches 40. With this construction it is possible to suspend the curtain from either hemmed passageway 35 or 37, with the top portion down hanging in front to present a valance-like effect (see Fig. 13); or from hemmed passageway 15 or 17, with the top portion concealed behind the curtain wall (see Fig. 14). The curtain may be hung from either hemmed passageway 15 or 35, to effect intermediate length adjustment; or from hemmed passageway 17 or 37, to effect minimum length adjustment.

By these varying constructions many different ornamental effects may be obtained in the operation of effecting length adjustment. The curtains are made in various sizes to fit different windows, each curtain size being primarily designed for a certain size window as determined by the length of its body portion 12, it being understood that the lowermost hemmed passageway 17 which is positioned at the line of merger of said body portion 12 with the surplus fabric top portion 11, is the normal line of suspension of the curtain when new, and the hemmed passageways 15 and 13 are reserved to provide new lines of suspension in case of shrinkage as by laundering. By spacing the hemmed passageways 13, 15, and 17 at such intervals as to approximate the amount of curtain shrinkage effected in laundering it possible to re-hang the curtains after laundering from another hemmed passageway and without any re-hemming or re-stitching. By this construction the curtains are also adaptable to

windows of different lengths, so that curtains obtained primarily for a certain set of windows, may be used even after a change of residence for windows of different length from those for 5 which the curtains were primarily designed, thereby avoiding the expense of new curtains with each change of residence. It will be observed that the curtains are all preferably provided with finished bottom, top and side edges, 10 to prevent unraveling of the curtain fabric. The top edge whether provided with a hemmed passageway 13, or pleat 41 (Fig. 10), will not unravel, owing to the presence of seam 18; and, in the construction of Fig. 10, of seam 42 also.

15 What is claimed is:

1. As an article of manufacture an adjustable ready-to-hang curtain having a body portion and a surplus fabric top portion, said top portion being adapted to be utilized variously to effect 20 different length adjustments of said body portion and when not so utilized conserved as an ornamental top or valance, a plurality of horizontally disposed hemmed rod-engaging passageways formed in said curtain top and positioned in parallel spaced relation to each other, the uppermost hemmed passageway being adjacent the top edge of the curtain, each of said hemmed passageways constituting a different line of suspension at which the curtain may be 25 hung from a suspension rod to effect length adjustment, the hemmed passageway selected as the line of suspension determining to what extent the top portion shall be utilized to extend said body portion and conserved to constitute said ornamental top or valance.

2. As a new article of manufacture a ready-to-hang adjustable length curtain, having a first horizontal rod-engaging hemmed passageway defining the finished top edge thereof, said passageway constituting the line of suspension for displaying the entire curtain without any valance or cuff down hanging to effect maximum length adjustment, a plurality of other rod-engaging hemmed passageways paralleling said first 40 hemmed passageway in spaced relation thereto and to each other, each of said hemmed passageways constituting other lines of suspension for the curtain when the same is shortened to an intermediate or to the minimum length thereof, 45 said other hemmed passageways being effective when used as the line of suspension to variously sub-divide the curtain into an adjusted length bottom portion and a complementary surplus fabric top portion, the latter variously foldable 50 adjacent the selected line of suspension to conserve and utilize said surplus fabric as a valance ornamenteally surmounting the bottom portion.

3. As an article of manufacture a curtain made of woven textile fabric or the like constituting the 55 body and top portions thereof, a horizontally disposed hem formed at the bottom edge of the body portion, the top marginal edge of the top portion having a horizontally disposed hem large enough to freely slidably receive a curtain rod, 60 said hem constituting a first hemmed rod-engaging passageway defining the finished upper edge of the curtain, the fabric in the top portion being transversely folded to form a loop paralleling but in spaced relation to said hemmed passageway 65 and large enough to freely slidably receive a curtain rod, and a line of stitches traversing the mouth of said loop and passing through both plies of fabric, to complete a second hemmed rod-engaging passageway positioned beneath and in parallel spaced relation to said first rod-engag- 70

ing passageway, said passageway defining another line of suspension for the curtain when hung to effect length adjustment.

4. As an article of manufacture an adjustable ready-to-hang curtain having a body portion and a surplus fabric top portion, said top portion being adapted to be utilized variously to effect different length adjustments of said body portion and when not so utilized conserved as an ornamental top or valance, a plurality of horizontally disposed 10 hemmed rod-engaging passageways formed in said curtain top and positioned in parallel spaced relation to each other, the uppermost hemmed passageway being adjacent the top edge of the curtain, each of said hemmed passageways constituting a different line of suspension at which the curtain may be hung to effect length adjustment, the distance between said passageways measuring generally the amount of shrinkage 15 of said curtain as in washing, the hemmed passageway selected as the line of suspension determining to what extent the top portion shall be utilized to extend said body portion and conserved to constitute said ornamental top or valance. 20

5. An article of manufacture a curtain made of woven textile fabric or the like, said curtain having a body portion, a horizontally disposed hem formed at the bottom edge of the body portion, constituting the weighted bottom edge 30 thereof, a top portion in extension of the body portion, said top portion having a horizontally disposed hem large enough to freely slidably receive a curtain rod, said hem constituting a first hemmed rod-engaging passageway defining the 35 finished upper edge of, and line of suspension for, the curtain, when hung at its maximum length, the fabric in the top portion being transversely folded to form a plurality of loops paralleling said first hemmed passageway in spaced relation 40 thereto and to each other, each of said loops being large enough to freely slidably receive a curtain rod, and a line of stitches traversing the mouths of each of said loops and passing through both plies of fabric, to complete a second and a third 45 hemmed rod-engaging passageway each positioned beneath and in parallel spaced relation to said first rod-engaging passageway and to each other, the said passageways defining other lines 50 of suspension for the curtain when the same is hung to effect intermediate or minimum length adjustment.

6. As an article of manufacture a curtain made of woven textile fabric or the like, said curtain having a body portion, and a top portion in extension of said body portion; said top portion comprising a horizontally disposed hem large enough to freely slidably receive a curtain rod formed adjacent the extremity thereof, said hem constituting a first hemmed rod-engaging passageway defining the line of suspension for the curtain when hung at its maximum length, the fabric in the top portion being transversely folded to form a plurality of loops paralleling said first hemmed passageway in spaced relation thereto 60 and to each other, alternate loops extending on opposite sides of the fabric, the distance between said loops measuring generally the amount of shrinkage of said curtain as in washing, and lines of stitches traversing the mouths of each of said loops in passing through both plies of fabric to complete a second and a third hemmed rod-engaging passageway each positioned beneath and in parallel spaced relation to said first rod-engaging passageway and to each other, the said 65 70

passageways defining other lines of suspension for the curtain when the same is hung to effect intermediate or minimum length adjustment.

7. As an article of manufacture a curtain made of woven textile fabric, said curtain having a body portion and a top portion in extension of said body portion; said top portion comprising, a horizontally disposed hem large enough to freely slidably receive a curtain rod, said hem constituting a first hemmed rod-engaging passageway defining the line of suspension for the curtain when the same is hung at its maximum length, an upstanding top edge surmounting said hem, the fabric in the top portion being transversely folded to form a plurality of loops paralleling said first hemmed passageway in spaced relation thereto and to each other, alternate loops extending on opposite sides of the fabric, the distance between said passageways measuring generally the amount of shrinkage of said curtain as in washing, and lines of stitches traversing the mouths of each of said loops and passing through both plies of fabric, to close the mouths of said loops and thereby complete a second and a third hemmed rod-engaging passageway each positioned beneath and in parallel spaced relation to said first rod-engaging passageway and to each other, the said passageways defining other lines of suspension for the curtain when the same is hung to effect intermediate or minimum length adjustment.

8. As an article of manufacture a curtain made of woven textile fabric, said curtain having a body portion and a top portion in extension of said body portion; said top portion comprising, a horizontally disposed hem large enough to freely slidably receive a curtain rod, said hem constituting a first hemmed rod-engaging passageway defining the line of suspension for the curtain when the same is hung at its maximum length, the fabric in the top portion being transversely and horizontally pleated at a distance from said hem, to form a loop extending on one side of the fabric, and thereafter transversely and horizontally pleated again to form a second loop extending on the opposite side of the fabric in close proximity to said first loop, the distance between said hem and said loops measuring generally the amount of shrinkage of said curtain as in washing, and a line of stitches traversing the mouths of each of

said loops to close the same and passing through the several plies of fabric to complete a second and a third hemmed rod-engaging passageway each positioned beneath and in parallel spaced relation to said first rod-engaging passageway, said second and third rod-engaging passageways defining another line of suspension for the curtain when the same is hung to effect length adjustment and being operable dependent upon the passageway used as the line of suspension to display the top portion as a down hanging valance or to conceal the same from view.

9. As an article of manufacture an adjustable ready-to-hang curtain having a body portion and a surplus fabric top portion, said top portion being formed by folding the fabric back upon itself from the top and securing the same along spaced parallel lines to form horizontally disposed hemmed rod-engaging passageways in spaced parallel relation to each other, said top portion being adapted to be utilized variously to effect different length adjustments of said body portion, each of said hemmed passageways constituting a different line of suspension at which the curtain may be hung from a suspension rod to effect length adjustment, the hemmed passageway selected as the line of suspension determining to what extent the top portion shall be utilized to extend said body portion.

10. As an article of manufacture an adjustable ready-to-hang curtain having a body portion and a surplus fabric top portion, said top portion being formed by folding the fabric back upon itself from the top and securing the same along spaced parallel lines to form horizontally disposed hemmed rod-engaging passageways in spaced parallel relation to each other, said top portion being adapted to be utilized variously to effect different length adjustments of said body portion, each of said hemmed passageways constituting a different line of suspension at which the curtain may be hung from a suspension rod to effect length adjustment, the distance between said passageways measuring generally the amount of shrinkage of said curtain as in washing, the hemmed passageway selected as the line of suspension determining to what extent the top portion shall be utilized to extend said body portion.

HUGO GELLER. 50
